UNITED STATES PATENT OFFICE.

CHARLES B. BOYNTON, OF NEW YORK, N. Y.

HOT-AIR FURNACE.

SPECIFICATION forming part of Letters Patent No. 289,967, dated December 11, 1883.

Application filed September 12, 1882. (No model.)

To all whom it may concern:

Be it known that I, CHARLES B. BOYNTON, of the city, county, and State of New York, have invented a new and useful Improvement 5 in Hot-Air Furnaces, of which the following is a full, clear, and exact description.

Reference is to be had to the accompanying drawings, forming part of this specification, in which similar letters of reference indicate corresponding parts in all the figures.

Figure 1 is a broken perspective view of my improved hot-air furnace. Fig. 2 is an inverted plan view of the radiator. Fig. 3 is a sectional elevation of the radiator, taken on the line *xx* of Fig. 2. Fig. 4 is a plan view of the annular bottom or supporting plate of the radiator; and Fig. 5 is a sectional elevation taken on the line *yy* of Fig. 4, showing the radiator and bottom plate thereof placed 20 upon the dome of the furnace.

The first object of this invention is to promote economy in the consumption of fuel in hot-air furnaces by retarding the products of combustion in their passage to the chimney 25 until all of the available heat is extracted therefrom by the ascending air. This object I accomplish by means of the construction and combinations of parts, substantially as hereinafter fully set forth and claimed.

Referring to the drawings, A represents the sheet-metal casing of the furnace, which is of ordinary construction, and B represents the corrugated cast-iron fire-pot, and C the corrugated cast-iron dome, which is contracted at 35 its upper end, as shown at *c*, Fig. 5, for receiving the annular cast-iron top or supporting plate, D, and radiator E, as clearly illustrated in said figure and in Fig. 1.

The radiator E is by preference made of 40 cast-iron, but may be made of sheet-iron or of both cast and sheet iron, and is made hollow, and by preference is in general form that of an annulus, but with the inwardly-projecting radial extension E', which extension is rounded, 45 and is adapted to fit upon or in and to form a good joint with the upper reduced end of the dome C, as shown clearly in Fig. 5. The passages F F' in the interior of the hollow radiator E and the extension E' thereof are the passages through which the products of combustion pass from the fire-pot to the chimney-opening H, and the space J, between the outer

surface of the inner wall, *f*, of the radiator and the outer surface of the wall *f'* of the extension E', is the air-heating space of the radiator, which space is made larger at the top than at the bottom by making the said walls *f f'* slightly diverging away from each other from the bottom toward the top, and this diverging of the walls *f f'* at the same time contracts 60 the size of the smoke and flame flues or passages F F' from the bottom toward the top, as shown.

The chimney-opening H is formed in the outer wall of the radiator, a little to one side 65 of the confluence of the passages F F', as shown in Fig. 2, and in the passage F, between the line of the passage F' and the chimney-opening H, is placed the partition K, thus causing the products of combustion issuing 70 from the fire-pot to traverse the entire circuit of the interior of the radiator, as indicated by the arrows in Fig. 2, before reaching the chimney-passage.

The bottom plate, D, of the radiator has 75 the inwardly-projecting extension D', which is curved at its end and formed with the lip *d*, which is adapted to fit in and form a good joint with the upper edge of the dome C, as shown in Fig. 5, and upon the upper surface of 80 this plate are formed the double sets of flanges *d' d'*, between which the tongues *b b*, formed on the lower edges of the radiator E, are adapted to fit, as shown in Fig. 5, for forming a perfectly gas-tight joint between the radiator 85 and plate, these parts being adapted to be bolted together by bolts passing through the corresponding lugs, *i i'*, formed, respectively, upon the radiator and the plate.

h h are braces extending from the walls *f'* 90 of the extension E' of the radiator to the wall *f* thereof, at their lower edges, for strengthening and rendering the radiator firm and rigid, and N is a covered opening in the outer wall of the radiator, through which the radiator may be cleaned. Constructed in this manner, the air entering the casing A will become heated from contact with the body B C of the furnace and exterior of the radiator E, in the ordinary way, and a portion of the air 95 will ascend through the central opening, M, of the plate D, into the heating-space J, and become still further heated from contact with the interior walls of the radiator. This heat-

ing-space, being larger at the top than at the bottom, accommodates the increase in volume of the air, due to its expansion from the additional heat which it takes up, and thus does 5 not in any manner retard or restrain the upward current of the heated air, but, on the contrary, facilitates and increases it; and the products of combustion from the burning fuel in the furnace, being compelled to traverse the whole circuit of the spaces F F' of the radiator, are retarded in their course to the chimney and longer exposed to the air to be heated, and they heat a greater exposed 10 surface of the radiator than they otherwise 15 would, so that the maximum amount of heat from the fuel will be utilized, thus greatly increasing the efficiency and heating-power of the furnace with a less consumption of fuel. Besides these advantages, the flanges d' d' of 20 the plate D and the tongues b b of the radiator, and the method of placing the plate and radiator upon the reduced opening c of the dome C, so that all points are about on a level with the top of the dome and below the 25 chimney-opening H, render the furnace perfectly gas-tight; as the easiest escape for the gas will be through the chimney-opening H, it being nearer to the top of the radiator, where the gas will collect, than any joint in the furnace. Furthermore, the flues or passages F F' being smaller at the top than at the bottom, 30 the smoke, gases, flame, &c., are caused to expand in a chamber gradually diminishing in

size upward, and are thus most limited and confined in their expansion at the top of the chamber, which causes the products of combustion, in their course to the chimney-opening, to hug the lower part of the flues or spaces F F', thus facilitating and increasing the draft of the furnace, while at the same time a considerable amount of heat is retained or retarded 35 at the top of the radiator.

Having thus described my invention, what I claim as new, and desire to secure by Letters Patent, is—

1. In a hot-air furnace, the dome-like radiator consisting of the annular chamber E, the central chamber, E', and passage F', connecting the said chambers together, the sides of the said chambers and passages being contracted toward and at the top, whereby the air-space between the same is widened at the upper end, substantially as and for the purpose set forth. 45

2. In a hot-air furnace, the combination, with 55 the annular chamber E, central chamber, E', and passage F', of the common bottom plate, D D', with the grooved flanges d' d', extending around its edges, and adapted to receive the tongues b of the sides of the annular chamber and passage, gas-tight, substantially as and for the purpose set forth. 60

CHARLES B. BOYNTON.
